UNITED STATES PATENT OFFICE.

EDWIN H. UNDERWOOD, OF BAINBRIDGE, GEORGIA.

CATTLE-GUARD.

1,326,622.

Specification of Letters Patent.

Patented Dec. 30, 1919.

Application filed March 29, 1919. Serial No. 285,949.

To all whom it may concern:

Be it known that I, EDWIN H. UNDERWOOD, a citizen of the United States, residing at Bainbridge, in the county of Decatur and State of Georgia, have invented certain new and useful Improvements in Cattle-Guards, of which the following is a specification, reference being had to the accompanying drawings.

10 This invention relates to certain improvements in cattle guards, and it is an object of the invention to provide a novel and improved device of this general character especially designed and adapted for use in connection with a roadway.

15 It is also an object of the invention to provide a novel and improved guard of this general character comprising a plurality of spaced members disposed transversely across 20 a roadway and forming a continuity of such roadway and which members are arranged over a pit.

25 The invention consists in the details of construction and in the combination and arrangement of the several parts of my improved cattle guard whereby certain important advantages are attained and the device rendered simpler, less expensive and otherwise more convenient and advantageous for use, as will be hereinafter more fully set forth.

30 The novel features of my invention will hereinafter be definitely claimed.

35 In order that my invention may be the better understood, I will now proceed to describe the same with reference to the accompanying drawings, wherein:

40 Figure 1 is a view in top plan illustrating a cattle guard constructed in accordance with an embodiment of my invention.

45 Fig. 2 is an enlarged vertical sectional view taken through my improved cattle guard transversely of the roadway, and

50 Fig. 3 is a vertical sectional view of my improved guard taken longitudinally of the roadway.

55 As disclosed in the accompanying drawings, R denotes a roadway entering within a field defined by the fence or inclosure F and which fence or inclosure F is provided with an entrance E between which the roadway R is directed.

60 Arranged at the entrance E and extending substantially entirely thereacross and also extending beyond opposite sides of the fence or inclosure F is a pit P of substan-

tial depth and which has its sides defined by the walls W formed of concrete or other suitable material.

60 The upper faces of the walls W have their inner marginal portions beveled, as indicated at 1, and inwardly of the bevels are provided with shoulders 2. Positioned upon the end or side shoulders 2 are the angle bars 3.

65 Each of the bars 3 is preferably L-shaped in cross section with its lower flange a inwardly directed and its second flange b vertically disposed.

70 Extending transversely of the roadway R and overlying the pit P are the spaced cylindrical bars 4 having their extremities secured, as at 5, to the flanges a of the bars B. The bars B preferably comprise galvanized iron pipe about two and one-half 75 inches in diameter, although I do not wish to be understood as limiting myself in this respect.

75 Underlying the bars B and substantially perpendicularly related thereto are the bracing or stiffening members 7, preferably angle bars, and said members are suitably clamped, as at 8, to each of the bars 4. The members 7 serve to maintain the bars 4 in fixed relative separated relation and also 80 brace and reinforce the same against bend under the influence of a load traveling thereover. It is also to be noted that the members 7 are of such a length as to extend across the pit and rest upon the side shoulders 1.

85 My improved guard as herein disclosed is of a character to readily permit motor-driven vehicles to travel thereacross but effectively serves to prevent cattle or the like 90 from having exit through the entrance E due to the inability of said animals to obtain a foothold on the bars 4 and which prevention is further facilitated by the pit P over which the bars 4 are arranged.

95 It is also to be noted that the shoulders 1 position the upper portions of the bars 4 substantially flush with the surface of the roadway so that my improved guard offers no hindrance to a vehicle traveling thereover.

100 From the foregoing description, it is thought to be obvious that a cattle guard constructed in accordance with my invention is particularly well adapted for use by 110 reason of the convenience and facility with which it may be assembled and operated,

and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

10 I claim:

1. A guard of the class described comprising, in combination with a substantially rectangular supporting structure adapted to be arranged within a pit provided in a roadway, a plurality of spaced and substantially parallel cylindrical bars having their end portions engaged with the supporting structure and extending transversely of the roadway, and members underlying the bars and secured thereto, said members being spaced longitudinally of the bars and substantially perpendicularly related thereto, said members having their opposite end portions engaged with the support, said members serving as braces for the bars, said bars having their upper surfaces substantially flush with the top portions of the supporting structure.

2. A guard of the class described comprising, in combination with a substantially

rectangular supporting structure adapted to be arranged within a pit provided in a roadway, a plurality of spaced and substantially parallel cylindrical bars having their end portions engaged with the supporting structure and extending transversely of the roadway, and members underlying the bars and secured thereto, said members being spaced longitudinally of the bars and substantially perpendicularly related thereto, 35 said members having their opposite end portions engaged with the support, said members serving as braces for the bars, and bars arranged substantially in parallelism with the members and to which the end portions 40 of the first named bars are secured, said second named bars being inset within the upper portions of the supporting structure, said second named bars having contact directly with the support, said first named bars and 45 second named bars having their upper surfaces substantially flush with the top portions 50 of the supporting structure.

In testimony whereof I hereunto affix my signature in the presence of two witnesses.

EDWIN H. UNDERWOOD.

Witnesses:

W. D. DOUGLASS,
W. J. CASTLEBERRY.
